UNITED STATES PATENT OFFICE.

FRANK NETSCHERT, OF NEW YORK, N. Y.

COMBINATION FURNITURE.

Application filed April 28, 1925. Serial No. 26,331.

The invention relates to combination furniture and has for its object to provide a combination crib and baby walker of novel construction arranged to be adjusted for its various purposes in a simple manner and capable of being folded into a compact package easily carried about from place to place. Other more specific objects will appear from the description hereinafter and the features of novelty will be pointed out in the claims.

In the accompanying drawings, which illustrate an example of my invention without defining its limits, Fig. 1 is a side elevation of the article of furniture set up as a crib; Fig. 2 is a cross section thereof on the line 2—2 of Fig. 1 and Fig. 3 is an end elevation looking at one end of the crib of Fig. 1. Fig. 4 is a plan view of a bed spring intended for use with the crib; Fig. 5 is a plan view showing the frame partly folded; Fig. 6 is a similar view showing the same in a fully folded condition; Fig. 7 is a plan view of the article showing the same adjusted as a baby walker; Fig. 8 is a side elevation thereof; Fig. 9 is a vertical section on the line 9—9 of Fig. 7; Fig. 10 is a view similar to Fig. 9, but showing the article used in a somewhat different manner; Fig. 11 is a perspective view showing the combination article and its parts in the form of a compact package capable of being carried about; Fig. 12 is a plan view showing a latch arrangement whereby the frame is locked in its unfolded position; Fig. 13 is a side view thereof; Fig. 14 is a fragmentary plan view showing a latch arrangement whereby the baby walker element is fixed in position upon the frame; Fig. 15 is a fragmentary side view thereof and Fig. 16 is a detailed section on the line 16—16 of Fig. 14.

As shown in the drawings, the article of furniture comprises a frame of suitable construction and dimensions and consisting of side members 20 and articulated end members 21 hinged to said side members by means of hinges 22. The end members 21 themselves comprise two sections hinged together at 23 so as to be capable of being folded or collapsed to the positions shown in Figs. 5 and 6 and extended or unfolded to the operative condition shown in Figs. 1, 2, and 3. Any suitable means may be provided for fixing the end members 21 in their unfolded condition. In the drawings, this means comprises latch members 24 slidably mounted upon the upper surfaces of one of the sec-

tions of each end member and provided with an open ended notch 25 arranged to be adjusted into connection with a pin 26 fixed upon the other section of each end member 21. To maintain the member 24 in slidable connection with their respective end members, they may be provided with slots 27 through which screws 28 extend into the given end member 21; in addition, each latch member 24 may be provided with a flange 29 depending downwardly therefrom into surface engagement with vertical surface of that section of the end member 21 with which the latch member is combined. To facilitate the actuation of the latch members 24, one end thereof may be constructed in the form of or provided with a manipulating handle 30 as shown in Fig. 13. The side frames 20 include supporting legs 31 mounted upon rollers or roller bearings 32 capable of being propelled over a surface with a minimum of effort. The side frames 20 further include lower side rails 33 which, when the article of furniture is set up as shown in Figs. 1, 2 and 3, provide supports for the bed spring 34, the latter being of any suitable construction; to maintain the bed spring in its intended position on the side bars 33, said bed spring may include projecting end members 35 recessed to fit upon said side rails as shown in Fig. 2.

When it is desired to utilize the article of furniture as a crib, the frame thereof is simply unfolded to the positions shown in Figs. 1, 2, and 3 and locked in this position by engaging the latch members 24 with the respective pins 26 and then placing the spring 24 in position upon the lower side rails 33. Suitable bedding 36 may be then placed upon the spring 34 as shown in Fig. 1 to provide a comfortable sleeping crib for an infant.

The article further includes a device which has been termed a baby walker and which consists of a frame comprising end members 37 having projecting ends 38 provided at their free end portions with supporting brackets 39 shaped for instance as indicated in Fig. 16 and connected with the end members 37 so as to lie flush with the upper surfaces thereof. The aforesaid frame of the baby walker further consists of side members 40 connected with the end members 37 and projecting beyond the same in one direction to support a table or tray 41. A flexible receptacle 42 preferably made

of canvas or other suitable material is connected with the members 37 and 40 which constitute the frame and depends therefrom in the manner indicated in Figs. 7 to 10 inclusive, said receptacle 42 being provided with openings 43 of sufficient size to accommodate the upper limbs of an infant and spaced apart at a predetermined distance as indicated in Fig. 7. A flexible support 44 of canvas or other suitable material depends from the tray section 41 of the baby walker in registry with the receptacle 42 to which it may be attached at 45 or of which it may form an integral part; it will be understood that the receptacle 42 and the support 44 are open at their opposed ends so as to communicate with each other for the purpose to be more fully described hereinafter. Intermediate side rails 46^a are provided upon the side members 20 of the main frame and themselves are provided at their proper points with recesses 47 for the reception of the brackets 39 whereby the baby walker is supported upon the main frame at an intermediate height thereon as shown in Figs. 8, 9, and 10. As shown in Fig. 9, the baby walker, when in position upon the main frame, may be utilized to support the baby in an upright position for walking or standing by projecting the limbs of the baby through the aperture 43, the side rails 46^a of the device providing rests whereby the baby may support itself against falling. As shown in Fig. 10, the device in question may also be used to support the baby in a sitting or reclining position in which case the feet and lower limbs may be extended into and contained in the support 44, a pillow 52 being placed in the receptacle 42 if desired, to add to the comfort of the infant in such reclining position.

To enable the baby walker to be supported upon the frame at a higher level, the top rails 46 of the main frame may be provided with recesses 47 similar to the recesses 47 of the intermediate rails 46^a. The baby walker may be combined with the top rails 46 in the same manner as previously set forth with respect to the intermediate rails 46^a and in such position may be used as a baby walker or as a hammock in the same manner as indicated in Figs. 9 and 10.

To prevent the baby walker from being accidentally disconnected or detached from the top rails 46 or 46^a, latch members 48 and 48^a may be slidably mounted upon the upper surfaces of said top and intermediate rails 46 and 46^a so as to be capable of being shifted over the brackets 39 as shown in Figs. 14 and 15. To permit the required adjustment of the latches 48 and 48^a and to slidably secure them upon the rails 46 and 46^a, said latches are provided with longitudinal slots 49 through which screws or the like 50 extend into the rails 46 as shown

in Fig. 14 or in a similar manner into the intermediate rails 46^a. One end of each latch 48 and 48^a may be provided with a handle 51 of suitable type to facilitate the adjustment of said latches to and from their operative positions.

It will be understood that the devices 32 on which the article of furniture is supported are of such a nature that comparatively slight effort only is required to propel the article over the floor or other surface upon which it is supported.

The article of furniture comprises an ideal nursery outfit and during the first six months of the infant's life may be used as a crib or bed for sleeping and thereafter may in addition be utilized as a baby walker to teach the baby how to walk and to maintain the infant in an upright position against falling. As the infant grows older and correspondingly increases in size, the baby walker may be adjusted or set at the higher level upon the top rails 46, so that the article is capable of efficient use throughout the entire period of the infant's life when support of this kind is required. In addition to its other functions, the article provides an ideal resting place for the baby in a reclining position in the manner indicated in Fig. 10. When not in use, the article may be folded as indicated in Figs. 5 and 6 and the parts thereof packed together as shown in Fig. 11 and secured in this condition by means of suitable strips 52 or the like. In this condition, all of the parts of the article of furniture are combined in a minimum of space and in an arrangement capable of being easily carried about. To facilitate this carrying about of the article in its folded condition, suitable handles 53 may be provided upon the top rails 46 as shown in Fig. 11. Because of its compactness when folded, the article may be carried along, for instance to the seashore, to enable the infant to enjoy all of the comforts of the nursery and to relieve the parent of the necessity for continuous and careful supervision of the infant.

Various changes in the specific form shown and described may be made within the scope of the claims without departing from the spirit of my invention.

I claim:

1. An article of the kind described comprising a frame capable of being propelled over a surface and having articulated end members capable of being collapsed, locking means for fixing said end members in their extended positions, side rails forming part of said frame and provided with recesses, an auxiliary frame, a flexible receptacle constituting a baby-walking device depending from said auxiliary frame and provided with apertures for the accommodation of the lower limbs of an infant, brackets 120

secured to said auxiliary frame and adapted to set into the recesses of said side rails for supporting said auxiliary frame and depending receptacle thereon and slidable latches 5 on said side rails for detachably securing said auxiliary frame thereon.

2. An article of the kind described comprising a frame capable of being propelled over a surface and having articulated end 10 members capable of being collapsed, locking means for fixing said end members in their extended positions, side rails forming part of said frame and provided with recesses, an auxiliary frame, a flexible receptacle 15 constituting a baby-walking device depending from said auxiliary frame and provided with apertures for the accommodation of the lower limbs of an infant, bracket secured to said auxiliary frame and adapted to set 20 into the recesses of said side rails for supporting said auxiliary frame and depending receptacle thereon, a tray extension forming

part of said auxiliary frame, a flexible support depending from said tray extension in front of and in communication with said 25 receptacle and slidable latches on said side rails for detachably fixing said auxiliary frame thereon.

3. An article of the kind described comprising a frame capable of being propelled over a surface and including top rails and intermediate rails each provided with recesses, a baby-walking device, rigid supporting members carrying said device and adapted to set into the recess of the top or 30 intermediate rails for supporting said walking device at different levels upon said frame and slidable latches on said rails for 35 detachably securing said rigid supporting members in the recesses thereof. 40

In testimony whereof I have hereunto set my hand.

FRANK NETSCHERT.
